UNITED STATES PATENT OFFICE

1,998,447

IMPULSE GENERATOR

Richard C. Coupland, United States Army,
Norfolk, Va.

Application October 2, 1934, Serial No. 746,534

6 Claims. (Cl. 89—27)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to an impulse generator employed in a synchronized control system such as is used to control the firing of machine guns between the blades of a rotating propeller of aircraft.

10 The purpose of this invention is to provide an impulse generator in which a power driven actuator is selectively positioned by either mechanical or electrical mechanism to supplement said mechanisms in moving a sear into or out of engagement with an impulse transmitting member.

15 With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

20 A practical embodiment of the invention is illustrated in the accompanying drawings, wherein:

Fig. 1 is a view in side elevation of a gun control assembly.

25 Fig. 2 is a longitudinal sectional view of the impulse generator showing the sear in engagement with the cam follower.

30 Fig. 3 is a similar view with the sear disengaged from the follower.

35 Figs. 4, 5 and 6 are sectional views on the corresponding lines of Figs. 2 and 3.

Fig. 7 is a sectional view of the cam ring.

Fig. 7A is a bottom plan view of the same.

Fig. 8 is a plan view of the plunger.

Fig. 9 is a plan view of the sear.

40 Fig. 9A is a side elevation of the sear.

Fig. 10 is a longitudinal sectional view of a modification showing the sear in engagement with the cam follower.

45 Fig. 11 is a similar view showing the sear disengaged from the follower.

Fig. 12 is a sectional view on the line 12—12 of Fig. 10.

Fig. 13 is a sectional view on the line 13—13 of Fig. 11.

50 Fig. 14 is a sectional view on the line 14—14 of Fig. 10.

Referring to Fig. 1, the gun control assembly consists of an impulse generator A connected to a trigger motor B by means of an impulse cable and cable housing C.

55 The impulse generator unit is arranged to constitute a compact integral part of the air plane engine synchronized thereto during or after assembly and it consists of a housing 5 in which is mounted a driven shaft 6 having a gear 7 by

which it receives its energy from a driving shaft 8 of the engine. The shaft 6 is supported by anti-friction bearings 9—9 and carries a cam 10 positioned in the lower portion of the housing 5. The shaft 6 rotates at a speed to give a cam impulse for each blade of the propeller of the airplane engine. When the shaft 6 is driven at the same speed as the propeller the cam will have the same number of lobes as there are blades on the propeller while the number of lobes will be doubled if the shaft is driven at half of the propeller speed.

A cam follower 11 arranged parallel to the driven or cam shaft 6 is slidably mounted in the housing 5 and has a foot 12 carrying a roller 13 adapted to engage the cam surface of the cam 10. Threaded in the other end of the follower is a plug 14 in which is secured the impulse cable 15 leading to the trigger motor B. The cable is sheathed in a tube 16 which is secured in a socket 17 removably held in place by a nut 18 threaded to the housing 5.

An electrical control unit within the housing 5 comprises an armature 19 and commutator 20 carried by the driven shaft 6 and a magnetic field 21 carried by a casing 22 mounted on anti-friction bearings 23—23 and carrying one of the bearings 9 of the shaft 6. The field 21 is of the permanent magnetic type or as shown of the self-excited type under excitation at all times so that the time lag required to build up a current flow will be a minimum.

The casing 22 carries brushes 24—24 wiping the commutator 20, and conductors 25—25 lead from the brushes through posts 26—26 to a switch 27 on the control stick 28 of the airplane. When the switch is closed it causes an increase in the current flow and a consequent increase in the magnetic pull between the armature and the field. This increase is sufficient to rotate the 40 casing 22 against the action of a spring 29 which will be further referred to later on. The rotational displacement of the casing is limited by cooperating stops 30—31 respectively on the casing 22 and the housing 5.

45 The upper end of the casing 22 carries an axially disposed shaft 32 on which is fixed a pinion 33. A slide 34 mounted in the upper part of the housing 5 includes a rack 35 meshing with the pinion. A cable 36 attached to the slide is actuated by a hand lever 37 placed on the control stick 28 of the airplane. This arrangement provides a mechanical operating mechanism for retracting the slide 34 and causing the casing 22 to the rotated. The spring 29 which rotates the 55 slide 34 and casing 22 to normal position is confined between the slide and a socket member 38 which is threadedly secured to the housing 5.

50 The cam follower 11 is provided with a lug 39 whereby it is held in inoperative position by a 60

sear 40. The sear is positioned below the casing 22 and is movable diametrically in a chamber 41 of the housing 5, the lower wall of the chamber having a channel 42 for guiding the sear and holding it against lateral displacement. A slot 43 in the sear accommodates the driven shaft 6. The sear is formed on each end with lugs 44 and 45 respectively employed when the sear is moved into and out of engagement with the cam follower.

10 The sear is actuated by a plunger 46 riding on the sear between the lugs 44 and 45. The plunger includes a head 47 having an elongated slot 48 for receiving the driven shaft 6 and a cam 49 formed thereon.

19 formed thereon.
The angular position of the plunger is con-
trolled by a ring 50 disposed between the lugs 44
and 45 of the sear and connected to the rotatable
casing 22 by means of a key 51. The portion of
20 the ring that overlies the plunger has a cam
surface 52 and is also provided with a channel
53 for the plunger whereby the plunger is con-
strained to be rotated with the ring.

The parts are normally in the position shown in Figs. 2 and 4, in which the sear 49 is held in engagement with the cam follower to prevent movement of the follower by means of the cam 52 on the ring 50 and also by means of the plunger 46. In this position the reciprocation of the plunger 46 by the cam 49 on the shaft 6 cannot disengage the sear from the cam follower.

When the casing 22 is rotated 180 degrees (Figs. 3 and 5) by closing the electric circuit or mechanically through the hand lever 37, the ring 50, carrying the reciprocating plunger 46, engages the lug 45 of the sear and initiates its disengagement from the cam follower while the power-driven plunger 45 strikes the lug 45 and completes the disengagement of the sear. When the electric circuit is opened or the lever 37 released, the spring 29 acts on the slide 34 to counter-rotate the casing 22. During this action the ring 50 and plunger 46 engage the lug 44 of the sear and move it into position to engage the cam follower.

40. The trigger motor unit B which forms the subject of a separate application includes a spring 54 which is generally common to this type of mechanism as seen in my prior Patent No. 1,770-
50. 125 of July 8, 1930. This spring acts on a slide 55 which receives the impulse transmitted by the cable 15 and the spring serves to restore the slide when the cam follower is not acted on by the cam 10. When the cam follower is depressed by the cam 10 the cable retracts the slide 55 and compresses the spring 54.

In the modification shown in Figs. 10 to 14 the sear and sear control mechanism are positioned above the electrical unit. Parts corresponding to those of the principal embodiment are designated by similar numerals with a prefix of one hundred. The ring 150 is integral with the casing 122. The plunger 146 is operated by an eccentrically placed pin 149 on the driven shaft 106. The pinion 133 is formed on a plate 154 closing the upper end of the casing 122. The lug 145 of the sear 140 is cut away to accommodate the slide 134. The modified device functions in the manner previously explained.

70

I claim:

1. In a synchronizing mechanism, a driven cam shaft, a cam follower, a reciprocally mov-

able sear engageable with the cam follower to hold it immovable, lugs on the ends of the sear, a plunger disposed between the lugs of the sear and selectively engageable therewith, a head on the plunger having a slot, a cam on the cam shaft disposed in the slot of the plunger head and adapted to reciprocate the plunger, a rotatable member disposed between the lugs of the sear and having a cam selectively engageable with the lugs of the sear, means whereby the plunger is angularly displaced with said member, and means for actuating the rotating member. 10

2. In a synchronizing mechanism, a driven cam shaft, a cam follower, a reciprocally movable sear engageable with the cam follower to hold it immovable, a plunger selectively engageable with opposite portions of the sear for moving it into and out of engagement with the cam follower, a head on the plunger having a slot, a cam on the cam shaft disposed in the slot of the plunger head and adapted to reciprocate the plunger, a rotatable member having a cam selectively engageable with opposite portions of the sear, means whereby the plunger is angularly displaced with said member, and means for actuating the rotatable member. 25

3. In a synchronizing mechanism, a driven cam shaft, a cam follower, a reciprocally movable sear engageable with the cam follower to hold it immovable, a plunger selectively engageable with opposite portions of the sear for moving it into and out of engagement with the cam follower, means on the cam shaft for reciprocating the plunger, a rotatable member having a cam selectively engageable with opposite portions of the sear, means whereby the plunger is angularly displaced with said member, and means for actuating the rotatable member. 35

4. In a synchronizing mechanism, a driven cam shaft, a cam follower, a reciprocally movable sear engageable with the cam follower to hold it immovable, a plunger for moving the sear into and out of engagement with the cam follower, means whereby the plunger is reciprocated by the cam shaft, a rotatable member having means for initiating movement of the sear into and out of engagement with the cam follower, means whereby the plunger is angularly displaced with said member, and means for actuating the rotatable member. 50

5. In a synchronizing mechanism, a driven cam shaft, a cam follower, a reciprocally movable sear engageable with the cam follower to hold it immovable, a plunger for moving the sear into and out of engagement with the cam follower, means whereby the plunger is reciprocated by the cam shaft, a rotatable member positionable to hold the sear in and out of engagement with the cam follower, means whereby the plunger is angularly displaced with said member, and means for actuating the rotatable member.

6. In a synchronizing mechanism, a driven cam shaft, a cam follower, a reciprocally movable sear engageable with the cam follower to hold it immovable, a plunger for moving the sear into and out of engagement with the cam follower, means whereby the plunger is reciprocated by the cam shaft, and means for moving the plunger into position for moving the sear into and out of engagement with the cam follower.
